UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

LASTING-MACHINE.

1,388,852.

Specification of Letters Patent. Patented Aug. 30, 1921.

Application filed March 15, 1918. Serial No. 222,601.

To all whom it may concern:

Be it known that I, JOHN W. COSGROVE, a citizen of the United States, residing at Medford, in the county of Middlesex and 5 State of Massachusetts, have invented certain Improvements in Lasting-Machines, of which the following description, in connection with the accompanying drawings, is a specification, like reference characters on 10 the drawings indicating like parts in the several figures.

This invention relates to machines for working uppers over lasts and is herein shown as embodied in a machine of the type 15 disclosed in United States Letters Patent to W. J. Drey No. 1,011,592.

The machine of the said prior patent comprises a staple inserting mechanism which is designed to form and insert staples of 20 fine wire through the upper and the channel lip or the rib or shoulder of the sole of a lasted shoe, while the shoe is in its original lasted condition with all the lasting tacks in place. The nose of the stapler is positioned 25 between two adjacent tacks to insert a staple, and this operation is repeated along each side of the shoe, the staples being so located that they will hold the parts permanently in lasted position during the succeeding 30 sewing or welt attaching operation, the lasting tacks having been removed before this latter operation is performed.

It is an object of the present invention to provide an improved side lasting machine 35 which will operate to cause the upper to conform to the last along each side thereof by a series of operations carried on progressively with the successive insertion of fastenings designed to secure the upper permanently in the structure of the shoe. As 40 the fastenings are inserted at the time the upper is made to conform to the last and are not subsequently removed, there is no opportunity for displacement of the upper, a 45 distinct advantage over former methods of manufacture. It is to be noted, moreover, that the steps of inserting lasting tacks and later removing the same, in accordance with the methods practically universally employed in the past, are now obviated by 50 the improved procedure herein disclosed. A great advantage, therefore, lies in the reduction in the number of machines and in the steps necessary to the making of a shoe.

55 In its illustrative embodiment, the inven-

tion comprises a pivoted member which cooperates with and is controlled by the fastening guiding nose of the fastening inserting mechanism to grip the upper and tension it over the last prior to the insertion of the 60 fastenings and to insert fastenings through the upper and into the channel lip or rib of the insole. The tensioning operation precedes the driving of each individual fastening in the line which extends along each side 65 of the shoe.

During the operations of pulling the upper over the edge of the last and securing it in place, the anvil against which the fastening is clenched is conveniently used as an 70 abutment on which the lasted shoe is fulcrumed in those slight rocking movements by which the operative assists in the operation of tensioning the upper about the last. To improve the operation of the machine, 75 the anvil referred to above is preferably made stationary to prevent movement of the work in the direction of drive of the fastenings and to provide an improved guide in presenting the work to the machine, and 80 means are provided to coöperate with said anvil in tensioning the upper about the last before the insertion of the fastenings, the arrangement being such that the fastening inserting mechanism inserts the fastenings 85 at the end of each tensioning operation.

In order to insure that the edge portion of the upper has been carried into proper relation to the channel lip or rib or shoulder of the sole before the insertion of the fastening, there is provided, preferably in the fastening guiding and driving mechanism, a tongue which wipes the upper over the edge of the sole and tucks it into the angle between the channel lip or rib and the feather 95 of the sole. In a practical form of the invention, the tongue or wiper is timed to move with the gripper means and assists in shaping the upper to the last.

In its illustrated preferred embodiment, 100 the invention comprises a fastening inserting mechanism having a fastening guiding nose which is movable forwardly as the fastening is being driven. Preferably the gripper means is arranged to coöperate with the movable nose to tension the upper about the last, the arrangement being such that the nose and the gripper means are moved to conform the upper to the last prior to the insertion of the fastening.

Other features of novelty which contribute to the carrying out of objects of the invention hereinbefore enumerated or of other objects of the invention which will be apparent from a consideration of the disclosure of the invention in the specification and drawings will be pointed out in the following detailed description and claims.

In the accompanying drawings:

10 Figure 1 is a side view partly in section of one embodiment of the lasting machine of my invention;

Fig. 2 is a detail view of the upper gripping mechanism;

15 Fig. 3 is a view similar to Fig. 1 showing the upper gripping mechanism with the parts in the position they occupy at the end of the lasting operation; and

Fig. 4 is a detail view in perspective of 20 the staple forming and driving members.

As herein above stated, Patent No. 1,011,592 shows a staple forming and setting mechanism which may conveniently be used to show an illustrative embodiment of the 25 fastening inserting element of the present invention. As shown, the standard 1 carries a stapling head 2 arranged to drive the staple fastenings horizontally into the work positioned against an abutment 3. The 30 standard carries also supports for a main shaft 4 which carries a cam disk 5 for operating the staple forming and driving mechanism. Referring specially to Fig. 4 of the drawings the said mechanism will be seen 35 to consist of an outside former 6 which is slotted at 7 to provide a bifurcated extremity which co-operates with an inside former (not shown) to bend a severed piece of wire into staple form. Carried by the outside 40 former on one side thereof is a cutter bar 8, the said bar being arranged to co-operate with the stationary cutter block (not shown) to sever the wire into proper lengths as the same is fed into position by the wire feeding mechanism shown at 9. For a complete 45 disclosure of the wire feeding mechanism reference should be had to the patent referred to above. The outside former 6 is further provided with rack teeth 10 arranged to be engaged by a segmental rack 11 on a lever 12 pivoted on the rock shaft 13 on the frame of the machine. The lever and rock shaft are caused to oscillate by 50 means of a cam roll carried by the lever and arranged to engage in the cam groove 14 in cam disk 5. To co-operate with the outside former in the forming and driving of staples there is provided a driver 15 which is guided in a passageway in the outside 55 former, the said passageway forming a continuation of the slot 7. It will be observed that the driver bar 15 is T-shaped in cross section to provide a staple driving portion 16 and a strengthening rib 17. Attached 60 to the upper end of the driver bar is a mem-

ber carrying rack teeth 18 which are arranged to mesh with a segment rack 19 on lever 20. This lever is secured to a rock shaft 21 pivoted in the frame of the machine and is provided at its upper end with a cam roll engaging in cam slot 22 in the cam disk 5. In the operation of the machine the outside former 6 is advanced by the lever 12 to cause the severing of a length of wire fed across its lower end and the formation 70 of a staple in co-operation with the inside former. Later the driver is actuated through the lever 20 in such timed relation that the inside former is retracted in time to permit the driver to engage the staple 75 and carry it through the staple guiding passage and insert the same into the work. Thus far the description applies equally well to the staple forming and setting mechanism of the patent referred to above. 80

At the forward end of the staple forming and driving mechanism there is provided a staple guiding nose piece 23 slidably mounted in a guideway and normally held in retracted position, against a shoulder (not 85 shown), by a spring 24 having one end engaging a pin 25 on the nose piece, a stud 26 being provided in the frame of the machine for engagement with the other end of the spring. Projecting into the nose 90 piece is a tongue 24^a which is ordinarily formed as an integral part of the outside former 6, it being obvious, however, that the said tongue may consist of a separate member fixedly attached to the outside 95 former. Toward the end of the forward movement of the outside former shoulders indicated at 25^a on the former engage with shoulders 26^a on the nose piece to push the nose piece forwardly toward the anvil member 27. At the same time that the shoulders 25^a and 26^a come into abutting relationship, the end 28 of the outside former engages with a shoulder at 29 on the nose piece. Inasmuch as there is a staple guiding 100 passage through the portion 30 of the nose piece, a continuous staple guiding passage in the nose piece and outside former is provided when the shoulders 28 and 29 are brought into contact with each other. When 105 the outside former has engaged the nose piece and carried it forwardly the driver advances along the continuous staple guiding and driver guiding passage and forces the fastening into the work. Inasmuch as 110 the tongue 24^a is formed as an extension at the forward end of the outside former the said tongue becomes the floor of the passageway along which the staple is moved in the driving operation. 115

Pivotedly mounted upon the stapler head is a member 31 which operates to clamp the upper of the shoe against the forward beveled end of the nose piece as clearly shown in Figs. 2 and 3 of the drawings. The 120

lower part 31^a of the member 31 is adjustably connected to the body portion of the member so that the gripper member may be adjusted in accordance with the height of the 5 lip or rib of the insole to pass and not engage said lip as it moves to clamp the upper against the nose piece. The front end of the nose piece has an upwardly extending portion designed to coöperate with the operative 10 end of the gripper member in all adjusted positions of the latter. This gripper member is pivoted at 32 and is provided with a bifurcated upper end 33 arranged to slidably engage a rod 34 between disks 35 slidably mounted on said rod. It will be observed that a spring 36 surrounds the rod between one disk 35 and a shoulder 37 on the 15 end of a link 38 secured to the rod. A second and lighter spring 39 surrounds the rod 34 between the other disk 35 and a bearing member 40 in which the rod is loosely and slidably mounted. In order that the gripper member 31 may be operated in proper timed relation with respect to the 20 nose piece, the link 38 is connected to the same lever 12 which operates in the outside former. Inasmuch as the outside former controls the movements of the nose piece there is thus established an operating mechanism 25 for the nose piece and gripper member which will insure their proper operation in gripping the upper to tension it over the last.

Mounted in the forward part of the stapler 30 head is the anvil member referred to above as abutment 3. The anvil member is rigidly attached to a slide 41 which is engaged by a heavy spring indicated by dotted lines at 42 to hold the anvil yieldingly in the position shown in the drawings. It is the intention that the anvil will be practically stationary to serve as a work guiding abutment, this feature being a distinct improvement over prior constructions. Inasmuch as it occurs 45 occasionally happens, however, that the work varies somewhat in thickness, it has been found desirable to provide for a slight yielding of the anvil under heavy pressure. It will be observed that the anvil is so shaped that it may be positioned to clamp the fastenings on one side of the channel lip or rib of the insole, also that it acts as an abutment to prevent movement of the work in the direction of drive of the fastenings.

At the time the work reaches this machine 50 the insole has been tacked to the last, the upper has been assembled on the last and temporarily secured in place thereon by one tack at the heel portion of the last, and the pulling-over operation has been performed in which three tacks have been driven at the toe portion. The shoe is now presented to the lasting machine of the present invention for the side lasting operation. When 55 the machine is at rest the gripper member 31

has its lower operative end moved away from the end of the nose piece so that the edge of the upper may be readily inserted in the space between these two members. At the same time the anvil member 3 is used to engage 70 the rib or channel flap of the insole to position the shoe as it is moved along in front of the staple guiding nose piece. When the machine is started in operation the gripper member is first moved to clamp the edge 75 portion of the upper against the nose piece. This takes place at the beginning of the forward movement of the outside former and as this forward movement continues the gripper member is forced more firmly into 80 engagement with the nose piece. During the latter part of the forward movement of the outside former the nose piece moves with said former, the upper being carried toward the upper surface of the last, thus tensioning 85 the upper about the last and at the completion of this forward movement the tongue 24^a also engages the upper as clearly shown in Fig. 3 of the drawings and assists in tensioning the upper and in forcing it into the 90 angle formed by the rib or channel flap and the feather of the insole, a fastening being driven at the completion of this movement and clenched against the anvil. It will be noted that the operative end of the gripper member 31 is moved toward the last by the nose piece, thus causing the upper to be gripped more firmly as the tensioning of the upper proceeds. The operative moves the shoe along step by step for a repetition of 100 these operations of lasting the upper and securing it in position as it is lasted along one side of the shoe. The other side is then lasted, after which the shoe is sent to another machine for the toe and heel seat lasting operations.

In certain classes of work it may be found desirable to make use of the arrangement in which a one-revolution clutch is provided so that the treadle has to be depressed for each 110 operation of the machine, this arrangement permitting more certain positioning of the work for each operation. However, the expert workman can perform the lasting operations so rapidly with the machine which now embodies the invention that the provision of a one-revolution clutch acts simply as a handicap. Hence the machine has been so arranged as to its clutch controlling mechanism that so long as the operative presses 115 the treadle the machine will continue to perform the operations described.

Having described my invention, what I claim as new and desire to secure by Letters Patent of the United States is:

1. In a machine of the class described, an abutment against which shoe parts on a last may be pressed, a fastening inserting mechanism having a fastening guiding nose, means for clamping a portion of the shoe 130

upper against the nose, and means for moving the clamping means and nose toward the abutment to press the shoe thereagainst to tension the upper about the last, the construction and arrangement being such that the clamping pressure on the upper increases with the tensioning of the upper.

2. In a machine of the class described, an abutment against which shoe parts on a last 10 may be pressed, a fastening inserting mechanism having a fastening guiding nose, a gripper member controlled by said nose and operative to clamp a portion of the upper against the nose, and means for moving the 15 gripper member and nose toward the abutment to press the shoe thereagainst to tension the upper about the last.

3. In a machine of the class described, an abutment against which shoe parts on a last 20 may be pressed, a fastening inserting mechanism having a fastening guiding nose, a gripper member for clamping a portion of the upper against the nose, and means for moving the gripper member and nose into 25 gripping relation, said means operating thereafter to move the gripper member and nose toward the abutment to press the shoe thereagainst to tension the upper about the last.

30 4. In a machine of the class described, an abutment against which shoe parts on a last may be pressed, a fastening inserting mechanism having a fastening guiding nose, a gripper member for clamping a portion of 35 the upper against the nose, and means for yieldingly actuating the gripper member into gripping relation to the nose, said means operating thereafter to move the gripper member and nose to tension the upper 40 about the last.

5. In a machine of the class described, a machine abutment for retaining the shoe parts against movement in the direction of drive of the securing fastenings, fastening 45 inserting mechanism, and means for clamping a portion of a shoe upper against said mechanism, said means and mechanism being movable toward the abutment to tension the upper about the last prior to the insertion 50 of the fastenings.

6. In a machine of the class described, a frame, a stationary anvil mounted in the frame and against which fastenings are clenched, means for intermittently inserting 55 the fastenings and means movable with respect to the fastening inserting means and controlled thereby for tensioning the upper of a shoe progressively about the last before the insertion of the fastenings.

60 7. In a machine of the class described, a frame, a stationary anvil mounted in the frame and against which fastenings are clenched, means for inserting the fastenings, and means including a gripper member con-

trolled by the inserting means for tensioning 65 the upper of a shoe about the last before the insertion of each fastening.

8. In a machine of the class described, a frame, a stationary anvil mounted in the frame and against which fastenings are 70 clenched, means for inserting the fastenings, and a gripper member controlled by the fastening inserting means for tensioning the upper of a shoe about the last before the insertion of each fastening. 75

9. In a machine of the class described, a frame, a stationary anvil mounted in the frame and against which fastenings are clenched, means for inserting the fastenings, and a spring-pressed gripper member coöperating with the fastening inserting means 80 for tensioning the upper of a shoe about the last before the insertion of each fastening.

10. In a machine of the class described, a stationary anvil against which fastenings 85 are clenched, means for inserting the fastenings, a pivoted gripper member coöperating with the fastening inserting means for tensioning the upper of a shoe about the last before the insertion of each fastening, and 90 means for yieldingly actuating the member into coöperative action with the inserting means.

11. In a machine of the class described, an anvil against which fastenings are clenched, 95 fastening inserting means, and means controlled by said first-mentioned means and movable to carry the upper of a shoe toward the anvil to tension the same and to wipe it into final lasted position under tension in 100 advance of the fastening inserting operation.

12. In a machine of the class described, an anvil shaped to furnish a backing for the channel lip or rib of an insole, fastening inserting means, and means comprising a 105 member designed to engage one side only of a portion of an upper and movable in coöperating with the fastening inserting means to seize the upper and tension it about the last prior to the insertion of fastenings. 110

13. In a machine of the class described, an anvil against which fastenings are clenched, fastening inserting means constructed and arranged to drive a fastening in a horizontal line through the upper and insole channel 115 lip or rib of a shoe, and means controlled by said first-mentioned means for tensioning the upper about the last and then wiping it over the edge of the insole prior to the insertion of each fastening.

14. In a machine of the class described, an anvil shaped to clamp a fastening on one side of the channel lip or rib of an insole, means for intermittently inserting fastenings through an upper and into the lip or 125 rib of the insole, said means comprising an outside fastening forming member, and means controlled by said member for pro-

- gressively tensioning the upper about the last and wiping it over the edge of the insole prior to the insertion of each fastening.
15. In a machine of the class described, a vertically stationary abutment against which shoe parts on a last may be pressed, fastening inserting mechanism comprising a fastening guiding nose, and means arranged to be controlled by the nose and to coöperate therewith for tensioning a shoe upper about the last progressively during the insertion of the fastenings.
16. In a machine of the class described, a vertically stationary abutment against which shoe parts on a last may be pressed, mechanism arranged to drive fastenings in a horizontal line through the upper of a shoe and into the channel lip or rib of an insole, and means comprising a single pivoted member arranged to cooperate with the inserting mechanism for seizing the upper and for thereafter tensioning it about the last before the insertion of the fastenings.
17. In a machine of the class described, a vertically stationary abutment against which shoe parts on a last may be pressed, mechanism constructed and arranged to drive fastenings intermittently into the upper of a shoe and into the channel lip or rib of an insole, and means comprising a yielding mounted member coöoperating with the inserting mechanism for seizing the upper and for thereafter tensioning it about the last progressively during the insertion of the fastenings.
18. In a machine of the class described, a vertically stationary abutment against which shoe parts on a last may be pressed, mechanism comprising a fastening guiding nozzle for inserting fastenings into the upper of a shoe, and means comprising a movable member controlled by the inserting mechanism and mounted independently of the nozzle and movable therewith for tensioning the upper before the insertion of the fastening, said means and mechanism coöoperating further to tuck the upper into the angle between the channel lip and the feather of the insole before the insertion of each fastening.
19. In a machine of the class described, a vertically stationary abutment against which shoe parts on a last may be pressed, mechanism for inserting fastenings into the upper of a shoe, and movable means controlled by the fastening inserting mechanism for pressing a portion of the upper against the mechanism, the means and mechanism thereafter coöoperating to tension the upper about the last progressively with the insertion of fastenings.
20. In a machine of the class described, a vertically stationary abutment against which shoe parts on a last may be pressed, mechanism for inserting fastenings into the upper of a shoe, and means for inserting fastenings into the upper of a shoe, and means for pressing a portion of the upper against the mechanism, the means and mechanism thereafter moving to tension the upper about the last and to tuck a portion of the upper into the angle between the channel lip and the feather of the insole before the insertion of the fastening.
21. In a machine of the class described, a vertically stationary abutment against which shoe parts on a last may be pressed, mechanism for inserting fastenings into the upper of a shoe, and means for yieldingly clamping a portion of the upper against the mechanism, the means and mechanism thereafter moving to tension the upper about the last before the insertion of the fastening.
22. In a machine of the class described, a stationary anvil against which fastenings are clenched, means for inserting the fastenings, and a gripper member for pressing a portion of the upper against the inserting means, said member and said means thereafter coöoperating to tension the upper about the last before the insertion of the fastening.
23. In a machine of the class described, a vertically stationary abutment against which a shoe may be pressed, mechanism for inserting fastenings into the upper of the shoe, and a gripper member for clamping a portion of the upper against the inserting mechanism, said member and mechanism thereafter coöoperating with the abutment to tension the upper about the last before the insertion of the fastening.
24. In a machine of the class described, a vertically stationary abutment against which a shoe may be pressed, mechanism for inserting fastenings into the upper of the shoe, a pivoted gripper member for clamping a portion of the upper against the inserting mechanism, said member and mechanism thereafter operating to tension the upper about the last and to tuck the upper into the angle between the channel lip and the feather of the insole, and means to yieldingly actuate the gripper member.
25. In a machine of the class described, a fastening inserting mechanism comprising a movable fastening guiding nose shaped to engage the upper of a shoe, an abutment mounted to yield against excessive pressure and against which the shoe may be pressed to prevent movement thereof in the direction of drive of the fastenings, and means coöoperating with the nose to tension the upper about the last before the insertion of each fastening.
26. In a machine of the class described, a fastening inserting mechanism comprising a fastening guiding nose shaped to engage the upper of a shoe, an abutment against which the shoe may be pressed, and means controlled by said mechanism for co-

- operating with the nose and the abutment to tension the upper about the last and to tuck a portion of the upper into the angle between the channel lip and the feather of the 5 insole before the insertion of the fastening.
27. In a machine of the class described, a fastening inserting mechanism comprising a movable fastening guiding nose shaped to engage the upper of a shoe, an abutment 10 against which the shoe may be pressed, and a gripper member controlled by said nose and coöperating therewith to tension the upper about the last before the insertion of the fastening.
- 15 28. In a machine of the class described, a fastening inserting mechanism comprising a fastening guiding nose shaped to engage the upper of a shoe, an abutment against which the shoe may be pressed, a gripper 20 member coöperating with the nose to tension the upper about the last, and means for actuating said member and said nose to carry a portion of the upper over the edge of the shoe sole.
- 25 29. In a machine of the class described, a fastening inserting mechanism comprising a fastening guiding nose shaped to engage the upper of a shoe, an abutment against which the shoe may be pressed, a gripper 30 member coöperating with the nose to tension the upper about the last, and interconnected means for operating the gripper member and the fastening guiding nose for carrying a portion of the upper over the edge of the 35 sole.
30. In a machine of the class described, a fastening inserting mechanism comprising a fastening guiding nose shaped to engage the upper of a shoe, an abutment against 40 which the shoe may be pressed, a gripper member coöperating with the nose to carry a portion of the upper over the edge of the sole, and means for moving both the gripper member and the nose toward each other to 45 grip the upper firmly preliminary to their upper tensioning action.
31. In a machine of the class described, a fastening inserting mechanism comprising a fastening guiding nose shaped to engage 50 the upper of a shoe, an abutment against which the shoe may be pressed, a pivoted gripper member coöperating with the nose, means for operating the fastening guiding nose, and a yielding connection between the 55 nose operating means and the gripper member for causing the latter to clamp the upper against the nose, the arrangement being such that the nose and the gripper member therafter move together to tension the upper 60 before the insertion of a fastening.
32. In a machine of the class described, an anvil shaped to clench staples on one side of the channel lip or rib of a shoe sole, means for stapling through portions of a 65 shoe upper and the lip or rib of the sole, said

means comprising a staple guiding nose and means yieldingly movable for clamping a portion of an upper against said nose and for acting in coöperation with the stapling means for pulling the upper into place before the insertion of a staple fastening. 70

33. In a machine of the class described, an anvil shaped to clench staples on one side of the channel lip or rib of a shoe sole, means for stapling through portions of a 75 shoe upper and the lip or rib of the sole, and a single pivoted gripper member acting in coöperation with the stapling means for pulling the upper into place before the insertion of a staple fastening. 80

34. In a machine of the class described, a stationary anvil against which staples are clenched, means for stapling through portions of the upper and sole of a shoe, a gripper member coöperating with the stapling means for pulling the upper into place before the insertion of a staple fastening, and means for yieldingly actuating the gripper member. 85

35. In a machine of the class described, 90 an anvil against which staples are clenched, means for stapling through portions of the upper and sole of a shoe, a pivoted gripper member coöperating with the stapling means for pulling the upper into place before the 95 insertion of a staple fastening, and interconnected means comprising a single lever for actuating the gripper member and the stapling means.

36. In a machine of the class described, 100 an anvil against which staples are clenched, means for stapling through portions of the upper and sole of a shoe, a gripper member pivoted to the frame of the machine and having a bifurcated upper end, a slideable 105 rod passing through said bifurcated end, springs on the rod, one on each side of the upper end of the gripper member arranged to press thereon to position the gripper member in work-receiving relation with respect to the stapling means, operating mechanism for the stapling means, and a connection between said mechanism and said rod, the arrangement being such that the gripper member is yieldingly pressed 115 against the stapling means to clamp the work thereon and is thereafter moved with the stapling means to position the work for the stapling operation. 110

37. In a machine of the class described, 120 an abutment against which the shoe may be fulcrumed and mounted to yield under excessive pressure, fastening inserting means comprising a fastening guiding nose, a wiper movable through said nose to lay the upper 125 over the edge of the sole, and means coöperating with the nose to grip the upper and with the wiper to tension the upper about the last before the insertion of the fastenings. 130

38. In a machine of the class described. 130

- an abutment against which the shoe may be fulcrumed and mounted to yield under excessive pressure, fastening inserting means, a wiper to lay the upper over the edge of the sole, and a member coöperating with the inserting means to grip the upper and with the wiper to tension the upper about the last prior to the insertion of each individual fastening.
39. In a machine of the class described, an abutment against which a shoe part on a last may be pressed, a fastening inserting mechanism having a movable fastening guiding nose, a tongue arranged to operate through the nose, and movable means controlled by the movement of said nose for clamping a portion of the upper against the nose while the said tongue wipes the upper over the edge of the sole.
40. In a machine of the class described, an abutment against which a shoe part on a last may be pressed, a fastening inserting mechanism having a fastening guiding nose and a tongue arranged to operate through the nose, and a member coöperating with the nose to grip the upper and with the tongue to tension the upper over the last and to wipe a portion of the upper over the edge of the sole.
41. In a machine of the class described, an abutment against which a shoe part on a last may be pressed, a fastening inserting mechanism having a fastening guiding nose and a tongue arranged to operate through the nose, and a member coöperating with the nose and the tongue to tension the upper over the last and to wipe a portion of the upper over the edge of the sole, said abutment being mounted to yield slightly under excessive pressure.
42. In a machine of the class described, an abutment against which a shoe part on a last may be pressed, a fastening inserting mechanism having a fastening guiding nose and a tongue arranged to operate through the nose, and a yieldingly mounted member coöperating with the nose and the tongue to tension the upper over the last and to wipe a portion of the upper over the edge of the sole, said nose and tongue being arranged to move toward the abutment to perform the operations described.
43. In a machine of the class described, an anvil against which the fastening is clenched, and a fastening forming and driving mechanism comprising an outside former for forming and guiding the staple, a fastening driver, and a fastening guiding nose separate from the outside former and arranged to be projected toward the anvil to guide the fastening into the work on the anvil.
44. In a machine of the class described, an anvil against which the fastening is clenched, and a fastening forming and driv-
- ing mechanism comprising an outside former for forming and guiding the staple, a fastening driver, a fastening guiding nose arranged to inclose the outer end of the outside former by which said nose is projected in the direction of the anvil, and a spring to return the nose to normal position.
45. In a machine of the class described, a fastening inserting mechanism comprising an outside former and a fastening guiding nose arranged to move toward the work during insertion of a fastening therein, spring means for returning the nose to retracted position, a stationary anvil for holding the sole normally against movement in the plane of action of the fastening inserting means, and means movable through said nose for wiping the upper over the edge of the sole while it is so held.
46. In a machine of the class described, a fastening inserting mechanism arranged to move toward the work in inserting a fastening therein, a stationary anvil for holding the sole normally against movement in the plane of action of the fastening inserting means, and means arranged to be controlled by the movable fastening inserting means and to coöperate therewith for tensioning the upper about the last while the work including the sole is so held.
47. In a machine of the class described, a fastening inserting mechanism arranged to move toward the work in inserting a fastening therein, a stationary anvil for holding the sole of a shoe normally against movement in the plane of action of the fastening inserting means, means for wiping the upper of the shoe over the edge of the sole, and a movable member designed to engage one side only of a portion of the upper and arranged to coöperate yieldingly with the movable fastening inserting mechanism to tension the upper about the last, said means and member being arranged to operate on the upper while the work is held by the engagement of the anvil with the sole as set forth.
48. A machine for lasting the upper of a shoe and progressively securing the upper to a sole comprising a fastening inserting mechanism arranged to drive fastenings through the upper and through the rib or channel lip of the sole and clench the same, said mechanism having a fastening guiding nose, and means for yieldingly clamping the upper against the nose for tensioning the upper about the last, a portion of the inserting mechanism serving as a fulcrum about which the shoe may be turned during the tensioning operation.
49. A machine for lasting a shoe upper and progressively securing the upper to a sole comprising a fastening inserting mechanism arranged to drive fastenings through

the upper and through the rib or channel lip of the sole and clench the same, said mechanism having a fastening guiding nose, means for clamping the upper against the nose, and means for moving the clamping means and nose to draw the upper about the last in the lasting operation.

50. A machine for lasting a shoe upper and progressively securing the upper to a sole comprising a fastening inserting mechanism arranged to drive fastenings through the upper and through the rib or channel lip of the sole and clench the same, said mechanism having a fastening guiding nose, 10 a member movable to clamp the upper against the nose, and means for moving the member and nose to draw the upper about the last in the lasting operation.

51. A machine for lasting a shoe upper and progressively securing the upper to a sole comprising a fastening inserting mechanism arranged to drive fastenings through the upper and through the rib or channel lip of the sole and clench the same, and means 20 coöperating with the said mechanism for gripping a portion of the upper and for tensioning the upper about the last prior to the insertion of the fastenings, a portion of the inserting mechanism serving as a fulcrum 25 about which the shoe may be turned during the tensioning operation.

52. In a machine for lasting a shoe, a movable gripper means in coöperation with a fastening inserting mechanism to grip a 30 shoe upper and then to tension it about the last prior to the insertion of the fastenings, said fastening inserting mechanism thereafter operating to insert fastenings through the upper and into the channel lip or rib 35 of an insole to secure the upper in lasted position.

53. In a machine of the class described, an anvil against which fastenings are clenched, fastening inserting means comprising a movable fastening guiding nose, and a wiping means, said nose and wiping means being movable toward the anvil to tension the upper of a shoe about the last prior to the insertion of the fastenings, 45 means for operating the wiping means, and 50

means including a spring for operating the nose.

54. In a machine of the class described, an anvil against which fastenings are clenched, and means for seizing the upper 55 of a shoe and thereafter tensioning it about a last and inserting fastenings to be clenched against said anvil, said means comprising fastening inserting mechanism and upper gripping means controlled by said 60 mechanism.

55. In a machine of the class described, an anvil constructed to engage the channel lip or rib or shoulder of an insole and arranged to serve as an abutment stationary 65 in the direction of the line of drive of the fastenings for positioning the work as it is moved transversely to said direction for the successive insertion of fastenings, mechanism for inserting fastenings successively 70 through a shoe upper and the lip or rib or shoulder aforesaid, and means controlled by said mechanism for tensioning the upper about the last and wiping it over the edge of the insole and into firm contact with the 75 lip or rib or shoulder of the insole progressively with the insertion of fastenings, said fastening inserting mechanism and means being operative to last the upper and secure it permanently in lasted position progressively along one side and then along the 80 other side of the shoe.

56. In a machine of the class described, an abutment shaped to engage the channel lip or rib of an insole to prevent movement 85 thereof in the direction of drive of the fastenings, inserting mechanism arranged to drive fastenings through a shoe upper and into the lip or rib of the insole, and means movable relatively to the abutment and to 90 inserting mechanism and above the lip or rib to engage the upper to clamp a portion thereof against the inserting mechanism, said mechanism and means thereafter co-operating progressively to tension the upper 95 about the last during the insertion of the fastenings.

In testimony whereof I have signed my name to this specification.

JOHN W. COSGROVE.
